UNITED STATES PATENT OFFICE

117,724

DESIGN FOR A VEIL SCARF

Julius Steinberg, New York, N. Y.

Application May 13, 1938, Serial No. 77,166

Term of patent 3½ years

To all whom it may concern:

Be it known that I, Julius Steinberg, a citizen of the United States, residing in the county of Kings, city and State of New York, have invented a new, original, and ornamental Design for a Veil Scarf, of which the following is a specification, reference being made to the accompanying drawing, forming a part thereof.

The figure is a plan view of a scarf showing my new design.

I claim:

The ornamental design for a veil scarf, substantially as shown.

JULIUS STEINBERG.
